UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL CASTING-MACHINE.

1,142,268

Specification of Letters Patent. Patented June 8, 1915.

Application filed June 27, 1914. Serial No. 847,585.

To all whom it may concern:

Be it known that I, DAVID S. KENNEDY, a citizen of the United States, residing at Brooklyn, in the county of Kings and State of New York, have invented certain new and useful Improvements in Typographical Casting-Machines, of which the following is a specification, reference being had thereto to the accompanying drawing.

10 My invention relates to typographical casting machines, such for instance as linotype machines of the general character described in Letters Patent of the United States to O. Mergenthaler, No. 436,582, 15 wherein an assembled line of matrices is presented temporarily to one side of a slotted mold, and molten metal is then forced into the mold from a pot by a suitable pump or plunger, all in the manner well-known in the art. The type metal is 20 delivered to the pot and is melted therein by suitable heating appliances, such as gas burners, and the like, which also serve to maintain it in molten condition, the temperature being usually regulated by a thermostat and connections therefrom.

In order to prevent the chilling of the metal as it is delivered to the mold, or for other reasons unnecessary herein to detail at 30 length, it is customary to maintain the mouth or delivery orifice at a different temperature from that of the main portion of the pot, this being effected by the employment of separate burners, one or more for 35 the pot proper, and another located in proximity to the mouth. To attain this end automatically, and by means of simple and convenient controlling apparatus, I preferably employ thermostatic devices and connections 40 therefrom to control the supply of fuel to the several burners, the said connections comprising adjusting means so that the respective amounts of fuel delivered to the burners may be relatively varied at will.

45 In the principal form illustrated, I have shown two separate and independent thermostats to control respectively the different burners, and the reason for this duplication is the greater simplicity and certainty involved in adjusting the heating effect of the burners relatively to each other. However, the use of similar results may be secured in connection with a single thermostatic controlling valve, and suitable adjusting means to vary relatively the amounts of

fuel passing therethrough, and this latter form is also illustrated. These features, as well as other points of improvement and construction, will be described in the specification and finally pointed out in the claims. 50

The present application is a continuation in part of an application filed by me June 5, 1913, Serial No. 771,916.

In the accompanying drawings, I have shown my invention in preferred form and by way of example, and as applied to the casting mechanism of a linotype machine. However, it will be understood that many changes and variations may be made therein, and in its mode of adaptation, which will still be comprised within its spirit. Also, it may be similarly applied to other forms of typographical casting machines, such for instance as those designed for the production of type, dies, etc. instead of slugs or linotypes, as herein presented. Generally speaking, I desire it to be understood that I do not limit myself to any specific form or embodiment, except in so far as such limitations are specified in the claims. 65 70 75 80

Referring to the drawings: Figure 1 is a perspective view of the pot, etc., partly broken away, having my invention applied thereto; Fig. 2 is a transverse vertical section, on an enlarged scale, through the valve box; Fig. 3 is a sectional detail on the line 3—3 of Fig. 2; Fig. 4 is a perspective of the thermostats and valve controlling apparatus detached; and Fig. 5 is a similar view of a modification. 85 90

Referring to Figs. 1, 2, 3 and 4, the pot A is provided in the usual manner with the outlet or mouth B, the pump or plunger C, the burners D and D' beneath the pot, and the burner E located in proximity to the mouth B. The supply of fuel to these burners is governed by suitable thermostatic devices, such as Q and Q², of aluminum or other material, and immersed in the molten mass. The thermostats Q and Q² are illustrated as located in proximity to each other, but may be situated at different points and at a greater distance if desired. The gas or other fuel employed enters through the inlet pipe F into the valve box G, where it is divided, one portion being delivered through the passage H and piping I to the burners D and D', and the other portion through the passage J and piping K to the burner E. In order to permit the ordinary swinging or 95 100 105 110

rocking movement of the pivotally mounted pot, etc., the supply piping preferably comprises a plurality of sections such as F and F¹ (Fig. 1) suitably jointed together as at F², at or near the pivotal axis of the pot. The main supply of fuel to the pipes H and J is controlled by the respective valve plungers N and O, arranged to contact with the ends of the passages K and L to shut off the flow of gas, or to be removed therefrom to permit the delivery of the required amount. The plungers N and O are each formed with restricted orifices K¹ and L¹, so that even when the passages K and L are closed, a small amount of gas is delivered to the burners in order to supply a constant or "pilot" flame, in the manner well understood in the art. The plungers N and O are mounted in suitable bores in the box G and are formed with circular grooves or recesses N² and O², which may be filled with plum-bago or other suitable substance, to act both as a lubricant and a seal. The plungers N and O are also provided with springs N¹ and O¹ located between the heads thereof and the exterior of the box G, in such manner that they tend to elevate the plungers and thus to permit the free passage of the gas to the burners. In order to protect the springs N¹ and O¹ and to exclude dirt, etc. therefrom, they are preferably surrounded by casings N³ and O³ mounted upon the valve box G. The movement of the valve plungers N and O in the opposite direction, or to their closing position, is effected by the independent controlling levers P and P², pivotally mounted at P¹, and with their remote ends resting upon the thermostatic rods Q and Q². At their outer ends, the levers P and P² are provided with adjustable contact screws R and S, which engage respectively the heads of the valve plungers N and O. It will be observed (see particularly Fig. 4) that the thermostats, the connected controlling devices, and the valve box, are all mounted upon a single bracket G¹, which may be connected to or disconnected from the pot at will, this arrangement thus constituting a convenient unitary attachment.

Generally speaking, when the temperature of the metal in the pot rises, the thermostats Q and Q² expand and shift the levers P and P² about the pivot P¹, and through the screws R and S depress the valve plungers N and O, so as proportionately to decrease the supply of fuel to the burners. When the temperature of the metal drops, the thermostats contract and the springs N¹ and O¹ elevate the valve plungers so as to increase the supply of gas to the burners.

As previously stated, it is generally desirable that the temperature of the mouth B or delivery portion shall be maintained at a level different from that of the main portion of the pot, and that this difference may

be regulated to any extent that may be required in the particular circumstances. These results I effect by the provision of the screws R and S, which may be adjusted and set to vary the relative positions of the valve plungers N and O, and thus to control the respective supplies of fuel.

As before mentioned, I preferably employ, separate and distinct thermostatic devices for each of the valves, and principally for the reason that the relative adjustment of the parts is thereby simplified and their desired controlling action rendered more certain. However, this result may be also secured by the employment of a single thermostat, as illustrated in Fig. 5, wherein the contact screws R and S are mounted at one end of a single lever P³, the opposite end of which rests upon the single thermostatic rod Q³. In these circumstances, the relative action of the valves is controlled by the independent adjustment of the screws with relation to each other, and their normal shifting is effected by the expansion and contraction of the single thermostat Q³ in substantially the manner before outlined.

As previously stated, my improvements have been shown only in preferred form and by way of example, and as applied to a specific form of machine. Obviously, many modifications and alterations therein, and in their mode of adaptation, will suggest themselves to those skilled in the art, without departure from the scope of the invention.

Having thus described my invention, its construction and mode of operation, what I claim and desire to secure by Letters Patent of the United States, is as follows:

1. In a typographical casting machine, the combination of a casting pot, a plurality of heating devices located adjacent different portions of the pot, and automatic means subject to the heat of the metal in the casting pot for controlling each of the plurality of heating devices, said means being adjustable at will to vary the heating effect of one heating device with relation to that of the other.

2. In a typographical casting machine, the combination of a casting pot, a plurality of burners active upon the pot, one located beneath the pot and another located remotely from the first-mentioned burner, fuel-supplying means for the burners, and automatic means subject to the heat of the metal in the casting pot for controlling each of the plurality of burners, said means being adjustable at will to vary the heating effect of one burner with relation to that of the other.

3. In a typographical casting machine, the combination of a casting pot having a mouth-piece through which the molten metal is ejected, two burners, one located beneath the pot and the other in proximity to the mouth-piece thereof, fuel-supplying means for the

burners, and automatic means subject to the heat of the metal in the casting pot for controlling each of said burners, said means being adjustable at will to vary the heating effect of one burner with relation to that of the other.

4. In a typographical casting machine, the combination of a casting pot, two burners active upon different portions of the pot, 10 and fuel supplying means comprising two controlling valves one for each burner, a chamber wherein the valves are located, a supply pipe leading to the chamber, and two branch pipes leading therefrom to the 15 respective burners, together with thermostatic means subject to the heat of the molten metal for operating the valves.

5. In a typographical casting machine, the combination of a casting pot having an interior chamber for the molten metal and a mouth piece through which the molten metal is ejected, two burners, one located beneath the pot and the other in proximity to the mouth piece thereof, fuel supplying means 25 for the burners, and two separate and independent thermostats located in the chamber for the molten metal for controlling the respective burners.

6. In a typographical casting machine, the

combination of a casting pot having a mouth 30 piece through which the molten metal is ejected, two burners, one located beneath the pot and the other in proximity to the mouth piece thereof, a fuel supply system including two controlling-valves for the burners, separate and independent thermostats disposed within said pot, for operating said valves, and means for adjusting the two valves relatively to their thermostats so as to vary the supply of fuel to the respective burners. 35

7. In a typographical casting machine, the combination of a casting pot having a mouth piece through which the molten metal is ejected, two burners, one located beneath the pot and the other in proximity to the mouth 45 piece thereof, a fuel supply system including two controlling valves for the burners, two separate and independent thermostats arranged in the pot, and two independently movable levers for operating the valves from 50 the thermostats.

In testimony whereof, I have affixed my signature in presence of two witnesses.

DAVID S. KENNEDY.
